Wheeler M. Morrison:

INVENTOR,

by *W. M. Morrison*
Attorney.

UNITED STATES PATENT OFFICE.

WHEELER M. MORRISON, OF TOWER HILL, ILLINOIS, ASSIGNOR OF ONE-HALF TO DAVID O. MILLER, OF SAME PLACE.

HORSE-DETACHER.

SPECIFICATION forming part of Letters Patent No. 391,381, dated October 16, 1888.

Application filed July 26, 1888. Serial No. 280,071. (No model.)

To all whom it may concern:

Be it known that I, WHEELER M. MORRISON, a citizen of the United States of America, residing at Tower Hill, in the county of Shelby and State of Illinois, have invented certain new and useful Improvements in Devices for Detaching Horses; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in horse-detachers, the same being designed to provide a means whereby the traces can be readily detached from the whiffletrees to release the horses from the vehicle; and it consists in the special construction and combination of the parts, as will be hereinafter fully set forth, and specifically pointed out in the claims.

In the accompanying drawings, Figure 1 is a perspective view. Fig. 2 is a sectional view. Fig. 3 is a vertical sectional view. Fig. 4 is a side view of a modification of my invention. Fig. 5 is a detail perspective view of one of the parts detached.

30 A refers to the pole of the vehicle, to which the singletree is pivotally secured in the usual manner, and to the ends of this singletree B are pivoted, by means of hollow bolts a, doubletrees C C. The tubes or bolts a are flanged at their upper ends, which lie within recesses formed in the upper surface of the doubletrees and extend to the under side of the singletree B, where they are provided with nuts a', which lie within countersunk recesses formed

40 in the under side of the singletree. The singletree B has pivoted to its upper surface levers b b, the outer ends of which are provided with rearwardly-extending and downwardly-bent portions b', which are provided with perforations through which pass the double crank-bars D, one portion thereof extending upwardly to the rear of the singletree to engage with the perforation in the rearward projection of the lever b, while the other end 45 extends under the singletree and is perforated to engage with the bar E, which passes through

the hollow bolt a. The inner ends of the levers have attached thereto suitable flexible connections, which extend to the body of the vehicle to be within easy reach of the driver. 55 By drawing upon these flexible connections d d the levers will be operated to depress the rods E and release the traces, as will be hereinafter described.

To the upper edge of the whiffletrees C C are secured angle-plates F F, which are provided centrally with vertical slots f, to permit vertical movement of the rods E, with eyes e at their upper ends. These eyes are adapted to lie over the inner ends of pivoted bars G 60 G, which are secured to the upper surface of the bent plates F F; and to the outer ends of these pivoted rods G G are secured bars h, which extend to the outer ends of the whiffletrees, the eyes in the ends of the traces being 65 placed over the ends of these rods.

When it is desired to release the traces, it is accomplished by simply drawing upon the connections d d, which operate the double crank-rods D to depress the rod or pin E, which 70 raises the outer ends of the pivoted bars G G and draws the rod h within the openings at the ends of the whiffletrees, thereby releasing the traces and detaching the horses from the vehicle. 75

In Fig. 4 of the accompanying drawings I have shown a slight modification, bell-crank levers G' being employed instead of the pivoted bars G. When such construction is used, the ends of the whiffletrees are provided with 80 outwardly-projecting pins, and the rods h are bent, as shown, so that the traces will be pushed off the pins, which project from the ends of the whiffletrees when the rods E are depressed. 85

The device hereinbefore described may either be used with doubletrees, as shown in the accompanying drawings, or with a singletree, and, if desired, the levers attached to the doubletree may be pivoted to the under side of the 90 same.

Having thus described my invention, I claim—

1. In a device for detaching horses, a singletree provided with upwardly-projecting plates 100 between which are pivoted bars G, rods extending beyond the end of the whiffletree con-

nected to the pivoted bars G, and a hollow bolt, a, through which passes a rod having an eye, e, connected to the operating mechanism, substantially as shown, and for the purpose set forth.

2. In combination with a singletree, B, levers b b, pivotally attached thereto and provided at their outer ends with rearwardly and downwardly projecting portions b', having perforations, double crank-rods D, engaging with the levers b and with the pins E, and pivoted bars G G, secured to the whiffletrees and provided with rods h h, the parts being organized substantially as shown, and for the purpose set forth.

3. In combination with the singletree B, the whiffletrees C C, pivotally attached thereto by

hollow bolts a, double crank-shaft D, having a forwardly-projecting end with a perforation, the upwardly-bent end engaging with the lever b b, pins E E, extending through hollow bolts adapted to engage with a perforation in the forwardly-extending end of the crank-shaft D, an eye formed in the upper end thereof for engaging with the pivoted bars, and rods h h, substantially as and for the purpose set forth.

In testimony whereof I affix my signature in presence of two witnesses.

WHEELER M. MORRISON.
